ELECTROLUMINESCENT PLATE AND FONT OF NUMERALS FORMED THEREON

Herbert F. Dickson, Jr., Seneca Falls, N.Y., assignor to Sylvania Electric Products Inc., a corporation of Delaware

Filed June 29, 1964, Ser. No. 80,622

Term of patent 14 years

(Cl. D64—12)

Fig. 1

FIGURE 1 shows a rear perspective view of an electroluminescent plate showing the base character repeated thereon, in accordance with my new design, the transparent front of the plate being plain, and

FIGURE 2 is a face view of the basic character and numerals formed therefrom.

I claim:

The ornamental design for an electroluminescent plate and font of numerals formed thereon, as shown and described.
